UNITED STATES PATENT OFFICE.

GROVER C. CHAMNESS, GILBERT E. CHAMNESS, AND ROBERT L. KANE, OF HERRIN,
AND HENRY M. KEITH, OF WEST FRANKFORT, ILLINOIS.

DISPENSING APPARATUS.

Application filed October 11, 1926. Serial No. 140,892.

This invention relates to a dispensing device for gasoline and the like, the general object of the invention being to provide a hand pump for forcing air into a tank to cause the discharge of the gasoline in the said tank into a dispensing tank, with means for automatically releasing the air pressure from the first tank after the second tank has been filled, such means also acting as a vent when the first tank is being refilled.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:

Figure 1 is a diagrammatic view of the complete system, with parts being shown in section.

Figure 2 is a sectional view through the check valve which is arranged between the storage tank and the auxiliary tank.

Figure 3 is an enlarged sectional view through the means for controlling the flow of air to and from the auxiliary tank.

Figure 4 is a section on line 4—4 of Figure 1.

Figure 5 is a sectional view through the pump.

Figure 6 is a horizontal section through the pump and showing the manifold thereof.

In these views, 1 indicates the tubular upright support for the delivery receptacle 2 which may be of the visible type. The storage tank is shown at 3 and the auxiliary tank is shown at 4, the tanks being connected together by the pipe 5 which contains the check valve 6, this valve being arranged to permit the fluid or liquid to flow from the tank 3 to the tank 4, but preventing the reverse flow. The pipe 5 has a continuation 5' which passes through the tubular support 1 and extends almost to the top of the receptacle 2. The storage tank is provided with the usual filling pipe 7 and the vent 8 and a small pipe 9 has its lower end connected with the filling pipe 7 and its upper end extending into the receptacle 2, with its end flush with the end of the pipe 5'. This pipe forms an overflow for the receptacle 2 and has attached thereto the

usual hose 11 for delivering the gasoline into a tank of a motor vehicle or the like. A valved drain pipe 12 connects the bottom of the receptacle 2 with the pipe 9 so that by opening the valve of this pipe, the receptacle 60 can be drained back into the storage tank 3.

A pump 13 of the double cylinder type is associated with the tubular support 1 and its two cylinders are connected together by the manifold 14, the handle of the pump being 65 shown at 15. A pipe 16 has its lower end connected with the manifold and its upper end is in communication with the top of a cylinder 17, said top being preferably formed of a screw cap. A piston 18 is arranged in the 70 cylinder and it is normally held against the top or cap of the cylinder by the coil spring 19 which is arranged on the piston rod 20 which depends from the piston and is guided in a spider 21 in the cylinder. A pipe 22 is connected with the cylinder adjacent its upper end and the said pipe extends downwardly and projects slightly into the auxiliary tank 4. A short pipe 23 connects the bottom of the cylinder with the pipe 9.

From the foregoing, it will be seen that when the pump is actuated, air will pass from the same, through the pipe 16, into the top of the cylinder 17. The pressure of this air will force the piston 18 downwardly until it uncovers the pipe 22, when the air in the cylinder will pass down the pipe 22 into the auxiliary tank 4, thus placing the gasoline in the said auxiliary tank under pressure so that it will be forced up the pipe 5' 90 into the receptacle 2, the check valve thus preventing the gasoline from being forced into the storage tank. When the gasoline reaches a level higher than the ends of the pipes in the receptacle 2, the gasoline will begin to return to the storage tank through the pipe 9. When enough gasoline has been forced into the receptacle 2, the pump is stopped and then the spring 19 returns the piston to its raised position and this will place the pipe 22 in communication with the pipe 23 so that the air pressure in the auxiliary tank is relieved by the air escaping into the cylinder from the pipe 22 and venting through the pipe 23 and the pipe 9. This 105 will permit more gasoline to pass from the storage tank into the auxiliary tank.

In order to provide a quick return for the piston, we may place a valve 24 in the top of the cylinder 17, which is opened by a hand 110

lever 25 so that by opening the said valve by hand, the air will quickly escape above the piston and permit it to return quickly and thus remove pressure from the gasoline in the tank 4 and vent the said tank so that it may be refilled from the storage tank.

By opening the valve in the pipe 10, the gasoline will flow from the receptacle 2 into the tank of the car and by opening the valve 10 in the pipe 12, the gasoline will drain from the receptacle 2 back into the storage tank.

When the receptacle 2 is being emptied, the pipe 9 acts as an air vent for replacing the gas in the said receptacle by air.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:—

1. In combination with a device for dispensing gasoline and the like including a storage tank, an auxiliary tank, a dispensing receptacle and pipes connecting these parts in series in the order named, an air pump, a cylinder having a piston therein, a spring for holding the piston at one end of the cylinder, a pipe connecting this end of the cylinder with the pump so that when the pump is actuated, the compressed air will move the piston, a pipe connected with the cylinder wall remote from said end of the cylinder, said pipe being connected with the auxiliary tank so that when the piston is lowered by the operation of the pump, the said pipe will be uncovered and air will enter the same and pass to the auxiliary tank and force liquid therefrom into the receptacle and a vent associated with the cylinder for venting the pipe and the auxiliary tank when the piston is in raised position.

2. In combination with a device for dispensing gasoline and the like including a storage tank, an auxiliary tank, a dispensing receptacle and pipes connecting these parts in series in the order named, an air pump, a cylinder having a piston therein, a spring for holding the piston at one end of the cylinder, a pipe connecting this end of the cylinder with the pump so that when the pump is

actuated, the compressed air will move the piston, a pipe connected with the cylinder wall remote from said end of the cylinder, said pipe being connected with the auxiliary tank so that when the piston is lowered by the operation of the pump, the said pipe will be uncovered and air will enter the same and pass to the auxiliary tank and force liquid therefrom into the receptacle, a vent associated with the cylinder for venting the pipe and the auxiliary tank when the piston is in raised position and a hand operated vent valve in the top of the piston.

3. A device for dispensing gasoline and the like comprising a storage tank, an auxiliary tank in communication therewith, a check valve for preventing the return of the gasoline in the auxiliary tank to the storage tank, a dispensing receptacle, a pipe connected with the auxiliary tank and extending through the receptacle to a point adjacent the upper end thereof, a vent pipe connecting the upper part of the receptacle with the storage tank, a discharge pipe connected with the bottom of the receptacle, a cylinder, a pipe connecting the upper part thereof with the auxiliary tank, a pipe connecting the lower end of the cylinder with the vent pipe, a hand operated pump, a pipe for leading the air therefrom into the top of the cylinder, a piston in the cylinder, a spring for holding the same against the top of the cylinder, said piston moving downwardly, when the pump is actuated, to introduce compressed air into the cylinder, whereby the pipe leading to the auxiliary tank will be uncovered and air will pass from the cylinder into the said tank and force the gasoline therefrom into the receptacle and hand operated means for permitting the air to escape from the top of the cylinder, whereby the spring will raise the piston and place the pipe leading from the auxiliary tank to the upper part of the cylinder in communication with the pipe connected with the vent pipe, thus venting the auxiliary tank into the storage tank.

In testimony whereof we affix our signatures.
